UNITED STATES PATENT OFFICE.

WILLIAM E. ELCOME, OF PHILADELPHIA, PENNSYLVANIA, ASSIGNOR TO WESTERN ELECTRIC COMPANY, OF NEW YORK, N. Y., A CORPORATION OF ILLINOIS.

DESIGN FOR A FONT OF TYPE.

40,862.

Specification for Design.

Patented Sept. 6, 1910.

Application filed June 25, 1910. Serial No. 568,946. Term of patent 14 years.

To all whom it may concern:

Be it known that I, WILLIAM E. ELCOME, citizen of the United States, residing at Oak Lane, in the city and county of Philadelphia and State of Pennsylvania, have invented a certain new, original, and ornamental Design for Fonts of Type, of which the following is a specification, reference being had to the accompanying drawings, forming a part hereof.

The drawings indicate the design of a full font of type in accordance with my invention.

The design of my new ornamental font of type is accomplished by the ornamental ap-

plication to the letters and characters of the thorn of the hawthorn bush, such ornamentation being so arranged as to give to the appearance of the letters and characters an electric effect as shown in the drawings.

I claim:

The ornamental design for a font of type substantially as shown and described.

In witness whereof, I hereunto subscribe my name this fourth day of June A. D., 1910.

WILLIAM E. ELCOME.
